CLAIM

The ornamental design for a combination battery and holder assembly, as shown and described.

DESCRIPTION

FIG. 1 is a perspective view of a combination battery and holder assembly showing my new design;

FIG. 2 is a side view of the combination battery and holder assembly;

FIG. 3 is a top view of the combination battery and holder assembly;

FIG. 4 is a bottom view of the combination battery and holder assembly;

FIG. 5 is a front view of the combination battery and holder assembly; and,

FIG. 6 is a back view of the combination battery and holder assembly.

The broken lines in the figures depict portions of the article which forms no part of the claimed design.
